UNITED STATES PATENT OFFICE.

JAMES IIVEN MAY, OF NILES, OHIO.

ROTARY VALVE.

Application filed April 30, 1925. Serial No. 26,982.

To all whom it may concern:

Be it known that I, JAMES I. MAY, a citizen of the United States, and resident of Niles, in the county of Trumbull and State of Ohio, have invented certain new and useful Improvements in Rotary Valves, of which the following is a specification.

My present invention relates to improvements in rotary valves for internal combustion engines, and aims to provide a construction in which leakage of fluid past the valve will be prevented without undue friction.

The invention further aims to provide in connection with a rotary cylindrical valve having a peripheral port, a coacting member having a gas passage, which member will be held in contact with the valve with requisite pressure, but will be prevented from any movement away from the valve, and will be self-adjusting to take up wear.

With these and other objects in view, which will hereinafter appear, the invention includes the novel features of construction and arrangement and combination of parts hereinafter described and particularly defined by the appended claims.

An embodiment of my invention is illustrated in the accompanying drawings, in which:—

Figure 1 is a transverse vertical section through the upper portion of an engine cylinder with its associated inlet and exhaust valves.

Fig. 2 is a perspective detail of one of the valves, and

Fig. 3 is a horizontal section through the valve and its casing.

While in this drawing I have shown only a single cylinder it will be readily apparent that as many cylinders may be provided as desired, this involving mere duplication or multiplication.

Referring by reference characters to this drawing, the numeral 1 designates the engine cylinder containing the customary piston 2 and provided on opposite sides with inlet and exhaust valves 3 and 4 respectively, which are rotatably mounted in valve chambers formed in part by lateral projections 5 and 6 of the cylinder, and in part by lateral projections of the detachable cylinder head 7.

The valves and cylinder are cooled by water chambers 5^a, 6^a, and the cylinder head is also provided with a water space 7^a, which water spaces may be connected with the usual

circulatory system in the manner well understood by those skilled in the art.

Valve casting or casing 5 has the usual intake connection 5^b, and valve casing 6 the customary exhaust connection 6^b.

The valves are of cylindrical formation and as those on the inlet and exhaust sides and their cooperating parts are duplicates of each other, a description of one will suffice.

Each valve 3, for example (Fig. 2) has a port 3^a in one end communicating by a curved passage with a peripheral port 3^b.

The valve casing is provided with a space or chamber adjacent the end of the valve carrying the port 3^a, with which space the intake pipe communicates, the same being true as to the exhaust valve.

The peripheral port 3^a is adapted to cooperate with a tubular packing member 8, having its lower edge curved to conform to the periphery of the valve, such member 8 being slidably guided in the cylinder head, preferably in the manner hereinafter described, and having a closed upper end 8^a, and a lateral port 8^b cooperating with the port or passage 7^a in the cylinder head leading to the combustion chamber thereof. The cylindrical chamber within which the member 8 is located is extended upward as indicated at 7^b and is provided with a closure member 9 preferably connected thereto by screw threads as shown. Closure member 9 has a threaded opening in its upper end through which passes a hollow adjusting screw 10 which may be locked in adjusted position by locking or set screw 11.

The packing member 8 has a stem 8^c extending upward from the closed upper end 8^a thereof, the upper end of the stem being threaded and extending into the hollow screw 10. A nut 12 is screwed onto the threaded portion of the stem and bears against the lower end of the screw 10.

A helical spring 13 surrounds the stem, the upper end of the spring being fast to nut 12 (conveniently by having its end inserted in a hole in the nut as shown), and the lower end of the spring being fast to the stem, conveniently by passing said end through a transverse hole as shown. In adjusting the parts the nut 10 is screwed down to proper position, which screwing action winds up the spring. Thereafter screw 10 is screwed down until its upper end bears on the upper face of nut 12 and is locked in position by set screw 11.

Supposing now that there is any looseness due to wear for example on the edge of member 8 bearing on the valve, the spring will rotate nut 12 and tend to screw the same upward on the stem, but as upward movement of nut 12 is prevented by the lower end of screw 10 the member 8 will be moved down until arrested by its contact with the valve. I thus provide an automatically or self-adjusting ported packing member which cannot be unseated by pressure of gases due to back firing, or the like.

Preferably I provide an auxiliary packing sleeve 14 between member 8 and its guide member 7^b, which sleeve has its lower edge shaped to conform to the surface of the valve and is pressed yieldingly towards the same by spring 15, as by the use of two sleeves. In this manner I secure a more flexible contact with the valve surface, but the outer sleeve may be omitted where desired.

A detachable cap 16 is preferably provided for the upper end of the tubular or guide part 7^b.

I prefer to provide packing rings 8^a and 14^a in connection with members 8 and 14, to guard against leakage.

The valves may, of course, be operated in the customary or any desired manner in proper relation to the piston movement, but as the operating means forms no part of the present invention, illustration and description thereof is deemed unnecessary.

Having thus described my invention, what I claim is:—

1. In an internal combustion engine, the combination with the cylinder, of a valve casing, a rotary ported valve therein, there being a passage leading from the valve casing to the cylinder, a ported packing member located in said passage, means for positively holding said packing member in contact with the valve, and means for automatically adjusting said holding means to take up wear.

2. In an internal combustion engine, the combination with the cylinder, of a valve casing, a rotary ported valve therein, there being a passage leading from the valve cas-

ing to the cylinder of substantially L-shape, a packing member in the shape of a hollow cylinder having a closed upper end and a lateral port, means for positively holding said packing member in contact with the valve, and means for automatically adjusting said holding means to take up wear.

3. In an internal combustion engine, the combination with the cylinder, of a valve casing, a rotary ported valve therein, there being a passage leading from the valve casing to the cylinder, a threaded spindle carried by the packing member, a nut on the spindle bearing against an abutment member, and a spring tending to rotate the nut. 65

4. In an internal combustion engine, the combination with the cylinder, of a valve casing, a rotary ported valve therein, there being a passage leading from the valve casing to the cylinder, a threaded spindle carried by the packing member, a nut on the spindle bearing against an abutment member, and a coiled spring encircling the spindle and having its ends connected respectively to the spindle and nut. 70

5. In an internal combustion engine, the combination with the cylinder, of a valve casing, a rotary ported valve therein, there being a passage leading from the valve casing to the cylinder, a threaded spindle carried by the packing member, a nut on the spindle, an adjustable abutment member supported from the cylinder and receiving the thrust of said nut, and spring means tending to rotate said nut. 80

6. In an internal combustion engine, the combination with the cylinder, of a valve casing, a rotary ported valve therein, there being a coacting passage leading from the valve casing to the cylinder, a cylindrical ported packing sleeve within said passage, a spring tending constantly to press said sleeve towards the valve, a ported packing member within said sleeve, means for positively and non-yieldingly holding said packing member pressed against the valve, and means for automatically adjusting said holding means to take up wear. 90

In testimony whereof, I affix my signature.
JAMES IVEN MAY.
